UNITED STATES PATENT OFFICE.

WILLIAM H. JACKSON AND JOHN H. HANKINSON, OF NEW YORK, N. Y.

DESIGN FOR A FIRE-PLACE OR GRATE.

SPECIFICATION forming part of Design No. 14,379, dated October 30, 1883.

Application filed August 3, 1883. Term of patent 7 years.

To all whom it may concern:

Be it known that we, WILLIAM H. JACKSON and JOHN H. HANKINSON, citizens of the United States, residing at New York, in the county of New York and State of New York, have invented and produced a new and original Design for Fronts or Casings of Fire-Places or Grates, of which the following is a specification, reference being had to the accompanying drawing, forming part thereof.

10 The drawing represents a front elevation of this newly-designed fire-place casing, and presents a view of the upper surface of the hearth in perspective.

15 The leading and characteristic feature of this novel design, viewed in elevation, consists in a wrought or raised surface representing in combination two kinds of braid or basket-work.

20 In this design five panels are represented. The three larger ones present the figure of rectangular open basket-work or braid M in relief, which covers their surface, and constitutes the principal ornamentation of the pilasters A B and of the frieze or horizontal casing

25 C. Each of the two smaller panels D present figures of three rosettes arranged vertically near the upper corners of the casing, and a plane serpentine border encircles and unites them, substantially covering the panels. Each of the five panels is bounded with figures rep-

resenting undulating close braid or basket-work P, which also constitutes the entire marginal boundary ornamentation of the frieze and of the pilasters of the casing. The horizontal plane of the hearth O presents the appearance of a wrought fluted surface representing outwardly-divergent lines or grooves, which harmonize with the general character of the design and with its undulating marginal border.

35 We claim as our invention—

1. The design for a fire-place or grate casing herein shown and described, the same consisting of the open rectangular basket-work 45 panels M on the pilasters A B and frieze C, and the marginal ornamentation representing close undulating basket-work P.

2. The five-panel design for fire-place or grate casing herein shown and described, for 50 the sides and top thereof, and the fluted ornamentation on hearth O, representing outwardly-diverging grooves or lines at the bottom of the fire-place.

Witness our hands this 20th day of June, A. 55 D. 1883.

WILLIAM H. JACKSON.
JOHN H. HANKINSON.
